UNITED STATES PATENT OFFICE.

WILLIAM R. HESLEWOOD, OF OAKLAND, CALIFORNIA, ASSIGNOR TO HYDRO VACUUM SMELTING CO., OF OAKLAND, CALIFORNIA, A CORPORATION OF CALIFORNIA.

COMBINED ROASTING AND SMELTING FURNACE.

1,121,559.

Specification of Letters Patent. Patented Dec. 15, 1914.

Application filed March 9, 1914. Serial No. 823,358.

To all whom it may concern:

Be it known that I, WILLIAM R. HESLEWOOD, a citizen of the United States, residing at Oakland, in the county of Alameda and 5 State of California, have invented new and useful Improvements in Combined Roasting and Smelting Furnaces, of which the following is a specification.

This invention relates to improvements in 10 a combined roasting and smelting furnace.

One of the objects of the invention is to provide a simple, substantial, easily operated furnace of the character described in which the ores to be smelted may be desul- 15 furized and deoxidized before it is entered into the fusion zone of the smelting chamber.

Another object of the invention is to provide means for conveying the heated gases 20 discharging from the furnace to the roasting chamber for the purpose of heating the roasting chamber.

Another object is to provide means for distributing the gases evenly throughout 25 the ore within the roasting chamber.

Further objects will hereinafter appear.

The invention consists of the parts and the construction and combination of parts as hereinafter more fully described and 30 claimed, having reference to the accompanying drawings, in which—

Figure 1 is a vertical longitudinal section.

Fig. 2 is a cross section on line x—x, Fig. 1.

Fig. 3 is an end view of one of the twyer 35 openings, showing the position of the damper.

Referring to the drawings, A indicates a smelting furnace or cupola, of suitable cross section and height, constructed of fire-brick 40 or like material, which is provided with an upper and lower set of twyer openings 2 and 3. Suitably supported above the chamber A is an ore roasting receptacle B, and connecting same with the furnace A is a 45 pipe 4 having a valve 5 mounted in its lower end through which the volume of ore fed to the lower smelting chamber may be controlled. Surrounding the roasting chamber is a series of vertically positioned pipes 6 50 which connect with the top of chamber A at their lower ends, and at their upper ends with the roasting chamber through a series of pipes 7, in each of which is mounted a controlling valve 8. The upper end of the 55 roasting chamber is connected, through a

pipe 9, with a feed hopper not here shown, and a valve 10 is provided at this point for the purpose of closing the upper end of the roasting chamber and also for the purpose of controlling the feed of ore to the roasting chamber. The upper end of the roasting chamber is also provided with a pipe 11 through which the hot gases conveyed into the roasting chamber, through the pipes 6, may be discharged by induced draft or suction. One of the vertically positioned pipes 6 is connected at its upper end with pipe 11, as indicated at 12, and the connection between the two is controlled by a damper or valve 13 of suitable construction. The particular type of furnace, indicated at A, is provided with angularly disposed twyers, as shown, and is particularly constructed for use in connection with oil burners of suitable construction, indicated at 14, and the 70 openings of the twyers are preferably controlled by dampers 15 as shown in Fig. 3.

In operation, the roasting chamber is first charged with ore through pipe 9 and valve 10. A fire is then started in the burners 14, 80 in the lower twyer openings, and the heat thus generated is conveyed through pipes 6 and distributed through the connections 7 throughout the ore within chamber B. The ore is here treated until it is completely desulfurized, if sulfurous ores are being treated, or until it is completely deoxidized, when iron ores or the like are being handled. Valve 5 is then opened to permit chamber A to be completely charged. The ore is 85 then directly acted on by the flame discharging through the lower twyers and is here melted and collected in a well in the usual manner.

The upper twyers are used for several 90 purposes, first, to increase the heat of the gases discharging from the smelting chamber for the purpose of increasing the temperature within the roasting chamber; and, second, for the purpose of adding carbon to 100 the gases thus discharging, when necessary. It often happens that the carbon admitted to the zone of fusion through the lower twyers is entirely consumed. It is, therefore, an advantage in some instances to inject more carbon or other gases through the upper twyers. The upper twyers are also used for emergency cases, that is, if the lower twyers should happen to freeze up it 105 would be possible to use the upper twyers to 110

clear the furnace. The connection formed between pipes 6 and 11 at 12 permits a portion or all of the gases to be by-passed without entering the roasting chamber, while the 5 several connections formed between pipes 6 and the roasting chamber permit a perfect distribution of the heated gases through the ores contained therein. Valves 8 provided at these points add greatly to produce a 10 uniform result.

A furnace constructed and arranged in the manner shown is simple in construction and the regulation of the gases passing through the roasting chamber may be perfectly controlled; the temperature and quality of same being regulated to a more or less degree by the upper set of twyers as above described.

The materials and arrangements of the 15 several parts of the furnace are such as the experience and judgment of the manufacturer may dictate.

Having thus described my invention, what I claim and desire to secure by Letters Patent is:—

1. In a furnace of the character described, the combination of a smelting furnace, a roasting furnace, means for conveying the heated gases discharging from the smelting furnace to the roasting furnace, means for distributing the gases evenly throughout the ore within the roasting furnace, an upper and lower set of twyers formed in the smelting furnace, and dampers in said twyers.

2. In a furnace of the character described, the combination of a smelting furnace, a roasting furnace mounted above the smelting furnace, a plurality of pipes connecting the roasting furnace with the smelting furnace, a pipe connecting the two furnaces through which the ore may be fed, and a valve in said pipe.

3. In a furnace of the character described, the combination of a smelting furnace, a 45 roasting furnace mounted above the smelting furnace, a plurality of pipes connected at their lower ends with the smelting furnace, a plurality of connections formed be-

tween the upper end of each of said pipes and the roasting furnace, and means for 50 conveying the ore from the roasting furnace to the smelting furnace.

4. In a furnace of the character described, the combination of a smelting furnace, a roasting furnace mounted above the smelting furnace, a plurality of pipes connected at their lower ends with the smelting furnace, a plurality of connections formed between the upper end of each of said pipes and the roasting furnace, a valve in each 55 of said connections, and means for conveying the ore from the roasting furnace to the smelting furnace.

5. In a furnace of the character described, the combination of a smelting furnace, a 60 roasting furnace, means for conveying the heated gases discharging from the smelting furnace to the roasting furnace, means for distributing the gases evenly throughout the ore within the roasting furnace, and 65 means including valves in the connecting passages for regulating the temperature and mixture of the gases passing through the roasting furnace.

6. In a furnace of the character described, 70 the combination of a smelting furnace, a roasting furnace mounted above the smelting furnace, a plurality of pipes connected at their lower ends with the smelting furnace, a plurality of connections formed between the upper end of each of said pipes and the roasting furnace, means for conveying the ore from the roasting furnace to the smelting furnace, a discharge pipe connected with the roasting furnace, and means 75 for by-passing a portion or all of the heated gases coming from the smelting furnace to said pipe.

In testimony whereof I have hereunto set my hand in the presence of two subscribing 80 witnesses.

WILLIAM R. HESLEWOOD.
